UNITED STATES PATENT OFFICE

ARNOLD AUGUST EGLI, OF HAMBURG, GERMANY, ASSIGNOR TO THE FIRM CHOCOLAT TOBLER HOLDING CO. AKTIENGESELLSCHAFT, OF SCHAFFHAUSEN, SWITZERLAND

POWER OPERATOR FOR TYPEWRITERS AND THE LIKE

Application filed April 12, 1926, Serial No. 101,385, and in Germany April 23, 1925.

The invention relates to improvements in or modifications of the key-controlled driving mechanism for typewriters, type-setting machines or the like, claimed in my U. S. A. Patent 1,652,430, and consists firstly in the fact that in order to eliminate the Z-shaped operable members or connecting rods for the cams or eccentrics illustrated in the constructional example of the main patent a pivoted yoke or cam carrier is formed which acts on the connecting rod, preferably on the end thereof. The pivoted yoke or cam carrier in this case preferably carries both the locking device and, if desired, the spring for holding the eccentric or cam in the position of rest. The pivoted yoke or cam carrier preferably receives its rearward movement from the connecting rod and is limited in its rearward movement by a stop. The movement of the striker or lever acting on the lock and the eccentric or cam is preferably limited by adjustable stops. This limitation is preferably effected by means of eccentrics, which may be common to a row of keys. According to the invention the keys are preferably supported in such a way that each key is mounted on a rotatable tube, a series of which are pushed telescopically one into the other.

The invention is illustrated by way of example in the accompanying drawing, wherein:

Figure 1 shows in side elevation a key with its associated eccentric and connecting rod,

Figure 2 is a plan of part of the keyboard, and

Figure 3 is a front elevation of part of the keyboard.

In the drawing, 1 denotes a key, the lever 19 of which is connected with a striker or push lever 2, which is held and accurately guided by a lever 13. The push lever 2 is connected at one end with a spring 3, while the other end faces a locking pawl 4. The pawl 4 prevents an eccentric disc or cam 5 from rotating in the direction of the arrow a. 6 is a continuously rotating roller, motor-driven or otherwise mechanically actuated, which rotates in the direction of the

arrow b indicated in Figure 1. 7 is a pivoted yoke or cam carrier in which the eccentric or cam is held. This pivoted yoke or cam carrier embraces the free end of a connecting rod 8, but is not positively connected to this rod. The rod 8 is adapted, with the help of projections 18, to release a desired movement of the machine, for example to bring about a preparatory adjustment of the setting of type bars which are arranged in magazines and can be moved out of them for the formation of lines.

The push lever 2 is suspended in such a way that in the position of rest the free lever arm remote from the spring 3 engages by a projection in a notch in the eccentric or cam 5 and that the tip of this lever lies close in front of the pawl 4.

The pawl 4 is oscillatably supported in the pivoted eccentric yoke or cam carrier 7 and locks the eccentric or cam 5 in a position in which it does not touch the roller 6. It is subjected to the action of a spring 9, which is likewise secured in the eccentric pivoted yoke. The pivoted yoke is held by a buffer 16 in such a way that no undesired contact of the eccentric 5 with the rotating roller 6 can occur. The spring 9 tends to hold the pawl 4 in the locked position.

If the key 1 is depressed, the push lever 2 is displaced towards the right, in which case it releases the pawl 4 and imparts an impulse to the eccentric 5. The eccentric 5 is quickly engaged by the roller 6 and rocks its pivoted yoke a short distance towards the right (Figure 1). The latter presses the connecting rod 8, which is guided in a rake 10, in the direction of the small arrow c towards the right, and thereby causes the release of the desired movement of the machine.

After a complete revolution the eccentric 5 is again caught in a known manner by the pawl 4. The push lever 2 yields upwards as known, until it strikes against the cushioning rail 17, which, being constructed as a rake, also serves it as a guide. The eccentric now remains inoperative until the key is released and is again struck. The connecting rod 8 may be subjected to spring action from the universal bar, not shown, and may return

immediately into the position of rest. The pivoted yoke bears against the buffer 16 following the pressure of the connecting rod. The initial and final positions of the lower 5 pivot lever 13 are limited by two spindles 12 which are eccentrically supported in the side wall of the keyboard. By this means accurate regulation of the push lever 2 is rendered possible and the strength of the impact 10 for the eccentric 5 and the sliding of the point off the pawl can now be adjusted to a hair's breadth. In this way with the simplest means a serious technical difficulty has been overcome.

15 The key 1 is guided in slotted plates 15 which protect the interior of the keyboard from dust and the like and carry small supports for holding the keys. 14 is a connecting piece or a carrier for the spindles 12. 20 With a large number of closely crowded keys supported by the method which is usual for example for line-typewriting machines it is impossible to construct a keyboard free from objection.

25 Figure 2 shows a number of keys and a number of levers 19 secured to a spindle 20 and to tubes 21, 22, 23, 24 and 25 which are mounted telescopically one in another on the said spindle.

30 In this constructional example a key 30 is shown mounted directly on the spindle 20, and a key 31 on a small tube 21 on the spindle 20. Similarly a key 33 is shown mounted on the tube 23, and a key 35 on the tube 25. The 35 tubes 22 and 24 are in fact also provided with keys at one end and with levers corresponding to the levers 19 at the other end, though these have been omitted in Figure 2 for the purpose of simplifying the drawing.

40 The spindle 20 is held in supports 40, the tube 21 in supports 41, and so forth, so that the individual keys and tubes cannot disturb one another. The dotted line in Figure 2 indicates the centre of the machine. The 45 arrangement is repeated symmetrically to right and left of the centre in seven rows of keys on each side rising step-wise one above the other so that there are in all fourteen groups like Figure 2, that is, eighty-four keys.

50 The supporting of the connecting rods spaced widely away from one another, as is rendered possible by this keyboard, has also other advantages, not further discussed here.

55 I claim:

1. In a machine of the character described, a plurality of keys, a continuously rotating roller, a plurality of rotatable and arrestable cams each adapted to be brought into contact 60 with said roller, a plurality of movable detents each adapted to engage a cam for positively preventing it from rotating and to be moved out of engagement with said cam by means of a said key, and a plurality of pivotable cam carriers each carrying a rotatable

cam by means of which it is adapted to be swung, and a plurality of members each adapted to be moved by a cam carrier.

2. In a machine according to claim 1, the said members being each adapted to be moved in a longitudinal direction only by a cam carrier without being positively connected therewith.

3. In a machine of the character described, a plurality of keys, a plurality of longitudinally movable members, a continuously rotating roller, a plurality of rotatable and arrestable cams, a plurality of pivotable cam carriers each carrying a rotatable cam by means of which it is adapted to be swung, 75 each of said cams being adapted to be pushed by means of a key in approximately the direction of the movement of the member and to be brought into contact with said roller without moving the cam carrier, each of said members being adapted to be moved by a cam carrier.

4. In a machine according to claim 1 in which said members are each adapted to move in a longitudinal direction only by cam carrier without being positively connected therewith, said carrier being arranged intermediate the roller and members, in such a manner that on rotation of its cam the carrier pushes against the said member. 90

5. In a machine according to claim 1 the said members being each adapted to move in a longitudinal direction only by cam carrier without being positively connected therewith, the cam carrier consisting of a pivoted 100 one-armed lever.

6. A machine according to claim 1, said cam carrier being adapted to act upon said member only in one direction of movement.

7. In a machine according to claim 1, the said detents being adapted to lock the rotatable cams after each movement of a said member while the corresponding key is depressed.

8. In a machine according to claim 1, the said detents being adapted to lock the rotatable cams after each full rotation of a said member while the corresponding key is depressed.

9. In a machine according to claim 1, the said detents being arranged on the said cam carrier.

10. In a machine as described, a plurality of operable members, a plurality of keys, a continuously rotating roller, a plurality of pivotable cam carriers, each carrying a rotatable cam, adapted to cooperate with the said roller, when a said key is depressed and to allow its carrier to move a said operable member, a plurality of movable locking means each adapted to engage a said cam, in combination with each of the said keys means adapted to cooperate with the said locking means so as to release it when the corresponding key is depressed and while the key is de- 120 125 130

pressed to allow the said locking means to return to its locking position immediately after the locking means has released its cam and before a second movement of the correspondingly operable member has occurred.

5 11. In a machine according to claim 10, the means cooperating with the locking means being pushing means adapted to push against the said locking means and to slide off from the said locking means immediately after having pushed it.

10 12. In a machine according to claim 10, the means cooperating with the locking means being pushing means, adapted to push against the said locking means to slide off from the said locking means immediately after having pushed it and to be adjusted so as to regulate the moment in which the pushing means slide off from the said locking means.

15 13. In a machine according to claim 10, the means cooperating with the locking means being adapted to push the said cam.

20 14. In a machine according to claim 10, a key and means for determining the ultimate positions of the said key, the said means being adapted to be adjusted.

25 15. In a machine according to claim 1, means controlled by said keys and adapted to push the said cam for initiating its rotation.

30 16. In a machine according to claim 1, one axle for the said plurality of pivotable cam carriers.

35 In witness whereof I affix my signature.

ARNOLD AUGUST EGLI.
